UNITED STATES PATENT OFFICE.

GEORGE FARGHER HIGHT, OF HUKERENUI, NORTH AUCKLAND, NEW ZEALAND.

DOOR STOP.

Application filed May 18, 1922. Serial No. 561,966.

To all whom it may concern:

Be it known that GEORGE FARGHER HIGHT, citizen of the Dominion of New Zealand, residing at Hukerenui, North Auckland, in 5 the Provincial District of Auckland, New Zealand, has invented a certain new and useful Improved Door Stop, of which the following is a specification.

This invention relates to stops for holding 10 doors in any desired open position, and provides a more convenient stop or holder than the devices at present in use.

According to the invention the stop or holder comprises a vertical rod capable of 15 movement vertically through a bracket secured to the door and in a casing also secured to the door. The rod has projecting from its lower end a pad of rubber or the like which is normally pressed downwards 20 on to the floor by a spring housed in the casing exerting pressure against a shoulder on the rod.

The bracket through which the rod passes has a portion formed with a sloped or 25 curved surface, above which and on the rod is a boss formed with a sloped or curved surface adapted to bear on the sloped or curved surface of the bracket, said boss also having projecting therefrom a handle by 30 means of which it can be turned. The boss is placed on the rod below a stop thereon while the bracket has a flat portion at the top of its sloped or curved surface.

The device and its operation will be further described with reference to the accompanying drawing, wherein:—

Figure 1 is a part elevation broken of a door with the improved stop fitted thereon, and showing the device operated to hold the 40 door from swinging.

Figure 2 is a similar view but showing the rod raised so as to leave the door free to swing, while

Figures 3 and 4 are detail views of the 45 bracket and the boss on the rod, the boss being turned so as to retain the rod in the raised position.

The rod 1 passes vertically through the bracket 2, which is secured to the door 3 50 at a convenient height from the floor 4, preferably just below the handle 5. The portion 2^a of the bracket 2 through which the rod 1 passes has an upper cam surface 6 sloped or curved as shown at the top of 55 which is a flat 7 (Figure 4).

To the bottom of the door 3 is secured a

casing 8 in which the rod 1 works, the lower end being provided with an enlarged portion 9 from which projects a pad 10 of rubber or the like. 60

A spring 11 housed in the casing 8 surrounds the rod 1 between the upper end of the portion 9 and the top of said casing, said spring tending to normally force the rod 1 downwards in order that the pad 10 will 65 make contact with the floor 4.

On the rod 1 above the bracket 2 is a loose boss 12 provided with a handle 13, and a lower cam surface 14 formed to ride on the upper cam surface 6 of the portion 2^a of the 70 bracket 2.

A stop 16 is secured on the rod 1 above the boss 12.

In order to keep the pad 10 raised clear 75 of the floor 4 and so leave the door 3 free to swing, the handle 13 is turned in the position shown in Figure 2, the operation causing the cam surface 14 of the boss 12 to bear and ride on the surface 6 of the part 2^a of the bracket 2, with the result that the 80 boss 12 is forced upwards against the stop 16 and raises the rod 1 whereby the pad 10 is lifted clear of the floor 4 and the spring 11 is compressed.

When the handle 13 is in the position indicated in Figure 2 the lower prominent portion of the boss 12 rests on the flat 7 on the part 2^a, so that the spring 11 is unable to force the rod 1 downwards. 85

To retain the door in the desired position 90 the handle 13 is moved from the position shown in Figure 2 to that shown in Figure 1, whereby the boss 12 moves downwards on the portion 2^a under the influence of the spring 11, which forces the pad 10 hard 95 down on the floor 4 and prevents the door from swinging.

The device can be fixed to either side of 100 a door, or it may be let into same, with the handle 13 projecting through a slot.

What I do claim and desire to obtain by Letters Patent of the United States of America is:—

1. A door stop comprising a bracket, a casing, a rod movable vertically in said bracket 105 and casing, an enlarged portion on said rod received in said casing, a spring confined between the top of said casing and said enlarged portion normally tending to project the rod to operative position, a floor engaging pad carried by the enlarged portion, a cam surface on said bracket, a boss loosely 110

mounted on the extremity of said rod above said bracket, a handle carried by said boss, a stop on said rod limiting the upward movement of the boss thereon, and a cam surface 5 on said boss adapted to cooperate with the first mentioned cam surface to effect longitudinal movement of said rod against the tension of said spring incident to the turning movement of said boss in one direction.

10 2. In a door stop, a bracket provided with a cam surface, a rod slidably mounted in said bracket, spring means normally tending to project said rod to operative position, a boss loosely confined on said rod, a stop carried by the rod preventing longitudinal displacement of the boss, a cam surface on said

boss adapted to cooperate with the first mentioned cam face whereby to effect longitudinal movement of said rod incident to turning of said boss, said bracket having a flat 20 surface adjoining the cam surface and adapted to be engaged by the prominent portion of the cam surface on the boss whereby the latter may be held in adjusted position, and a handle on said boss.

25 In testimony whereof I have affixed my signature in presence of two witnesses.

GEORGE FARGHER HIGHT.
